UNITED STATES PATENT OFFICE

WILLIAM YOUNG, OF DETROIT, MICHIGAN

SLEEPING CAR

Application filed October 29, 1930. Serial No. 491,878.

The present invention pertains to a novel sleeping car for use on railways.

The principal object of the present invention is to provide an upper and lower berth structure wherein the upper berth can be more conveniently manipulated than in the conventional constructions. The device of the present invention is distinguished from the more common upper berth structure by the fact that the upper berth slides vertically between operative and inoperative positions, while in the common constructions the upper berth swings on a horizontal axis lengthwise of the car.

In moving the upper berth from one position to another, according to the present invention, it is necessary only to slide the same on vertical guiding means provided therefor. Consequently, the bedding thereon may be prepared before moving it to inoperative position so that there will be no time lost for arranging the bedding when the berth is brought into use. When raised to its inoperative position, the upper berth is concealed in a suitable fixed structure which may have an ornamental appearance.

The invention also provides for the provision of certain appliances such as wash-basins, folding chairs and mirrors, for the use of the occupants of both berths. The car has a double wall structure in which these devices may be housed in such a manner as to be concealed when not in use and readily brought into use when desired.

The invention is fully disclosed by way of example in the following description and in the accompanying drawings, in which

Figure 1 is a transverse vertical section of a sleeping car constructed according to the invention;

Fig. 2 is a section on the line 2—2 of Fig. 1; Fig. 3 is a section on the line 3—3 of Fig. 1, and

Fig. 4 is a longitudinal vertical section of the car on the line 4—4 of Fig. 1.

Reference to these views will now be made by use of like characters which are employed to designate corresponding parts throughout.

The car is preferably of steel construction having vertical side walls 1 covered by a roof

2. The roof lies in one horizontal plane, extending directly from the upper edges of the wall 1, as distinguished from the more conventional construction in which the roof has a raised central portion running lengthwise of the car. The construction shown herein provides more space in the upper corners of the car, for a purpose which will presently appear. Along the walls 1 are mounted inner wall members 3 parallel to and spaced from the members 1, thereby forming a double wall structure with a compartment or space 4 between the inner and outer wall members 1 and 3 respectively.

On the floor 5 of the car are mounted seats 6 alternately in back to back relation and front to front relation, as in the conventional sleeping car arrangement. Between the backs of adjacent seats, however, are mounted vertical slideable partitions 7 for a purpose which will presently appear. The two seats 6 between adjacent partitions 7 are adapted to be converted into a lower berth, also in the manner well known in the art.

Each space between partitions 7, from the floor to the roof of the car, may be identified as a compartment, and the berth structure which is identical in all compartments will now be described with respect to one of the compartments. Longitudinal structural members 8 and 9 are mounted in the space 4 respectively along the seats 6 and in the upper corner formed by the members 1 and 2. The members 8 and 9 serve to support a vertical guide rod 10, at each seating compartment 85 preferably in the transverse center thereof and obviously in the space 4. An upper berth frame 11 is vertically slideable over the seats 6 in each compartment by means of a bracket 12 extending from each frame and slidably 90 surrounding the adjacent rod 10. The inner wall member 3 is slotted at 13, as shown in Fig. 2, to permit vertical sliding of the brackets 12. These brackets have offset ends 14 for attachment to the frame 11 at points outside the edges of the slot 13.

Between the offset ends is mounted a vertical panel 15 fixed to the car structure as shown more clearly in Fig. 1, whereby the slot 13 is concealed when the berth is in its raised position. The ex- 100

posed face of the panel may support a mirror, and window openings 16 and 17 are formed in each seating space at opposite sides of the panel and respectively in the upper and lower parts of the seating compartment.

Beneath the bracket 12, each rod 10 is surrounded by a coil spring 18 resting upon the structural member 8 and balancing the berth 11. Between the backs of adjacent seats 6 is inserted a rail 19 suitably secured to the inner wall member 3. This rail has a vertical groove 20 receiving a tongue or bead 21 extending from the outer edge of the adjacent partition 7. The opposite faces of the rail have grooves 22 receiving rollers 23 carried by the ends of adjacent berths 11. The inner vertical edge of each partition 7 is enlarged as at 24 and formed with angles 25 which receive and guide the inner corners of adjacent berths, thus each berth is guided at its four corners as well as by means of the brackets 12 on the rod 10.

The bottom of each berth carries a rotatably mounted disk 26 with two locking rods 27 pivotally attached to eccentric points thereof and extending lengthwise of the berth. Each berth is adapted to be received in an upper structure 28 when not in use. The transverse walls have notches 30 adapted to receive the free ends of the rods 27, whereby to lock and support the berth in the raised position shown in Figs. 1 and 2. A handle 31 extends from the disk 26 for operating the rods 27.

The spring 18 is preferably of insufficient strength to support the berth 11 in raised position, so that the berth will drop when the locking rods 27 are released from the notches 30. In descending, the berth is limited by the engagement of the lower rollers 23 with the lower ends of the slots 22. Adjacent each partition 7 is a shaft 32 preferably journaled in the back of one of the seats 6. The shaft is concealed and carries gears 33 meshing with the racks 34 secured vertically to one of the sides of the partition. Each of these shafts is accessible to the exposed end of the corresponding seat 6, as shown in Fig. 4, by means of a suitable crank. The partitions are operated by turning the respective shafts 32 and are preferably raised before the berths 7 are lowered, so that the inner corners of the berths will have bearing in the angles 25 of the partitions 7.

For the purpose of raising the berths to the concealed position, an operating shaft 35 is journaled in the back of one of the seats 6 of the corresponding compartment and is equipped with a pulley 37 in the wall space 4. Another pulley 38 is journaled in the wall space vertically above the member 35, and still another pulley 39 is journaled at a point spaced horizontally from the member 38 in the direction towards the guide rod 10. The bracket 12 has a pulley or roller 40

mounted therein. A flexible member 41, such as a cable or steel ribbon is passed over the pulleys 38 and 39 and under the roller 40, having one end secured to the pulley 37 and the other end 42 anchored to a suitable fixed member in the car structure. The shaft 35 may be engaged by the crank, and when turned in counter clockwise direction with reference to Fig. 4, winds the member 41 on the pulley 37 and raises the berth 11. When raised to its upper limit, the berth is concealed in the structure 28 and is locked in this position by operation of the handle 31 as already described.

The space 4 is common to both the upper and lower berths and may be utilized to contain appliances for the use of the occupants of both berths. In Figs. 2, 3 and 4 are shown transverse partition members 43 extending between the wall members 1 and 3 and defining vertical compartments 44 at both sides of the rod 10 and of ample size to contain piping 45 for the plumbing fixtures, and for heating the compartments.

At opposite sides of the vertical panel 15, the inner wall 3 comprises movable panels 46 and 47 mounted on horizontal hinges 48 at their lower edges and adapted to swing from the inner wall 3 into the seating compartment. It will be seen in Fig. 4 that these panels lie between the member 15 and the upper window openings 17.

The inner surface of the panel 46 carries a wash basin 49 exposed in the space 4 when the panel is raised, as may be seen by reference to Fig. 2. The basin is so mounted on the panel as to assume an operative and useful position when the panel is suspended vertically from its hinged edge. A flexible or swivel pipe coupling 50 connects the basin to one of the pipes 45 and it will be evident that similar coupling means may be extended from the water supply pipes to the taps associated with the basin. Hot and cold water may obviously be supplied through separate pipes 45.

To the inner face of the panel 47 is attached a seat member 51 by means of a hinge 52 at its upper edge. When the panel 47 is released, it hangs vertical from its hinges 48. The hinge 52 permits the seat member 51 to be then extended into a horizontal position. Thus, the occupant of the upper berth is provided with a seat which is particularly useful when the occupant is dressing or undressing. Obviously, similar plumbing facilities may be provided for the lower berth.

In the upper forward corner of the enclosure 28 is mounted a spring roller 53 as shown in Fig. 1. This roller carries a curtain 54 attached to the forward edge of the berth frame 11, so that when the berth is lowered, the curtain is drawn down therein. This curtain may be so constructed as to per-

mit easy entrance into the berth although normally concealing the berth.

A ventilating shaft 55 extends through the entire length of the car and is provided with 5 ventilating ports 56 opening into the upper structure 28. These ports 56 are to be provided with any suitable damper or valve mechanism of a type permitting the bedding to be aired while the berth is in its closed position. A hinged shelf 57 is hinged to the edge of the ventilating shaft and closes the space between the edge of the berth 11 and the ventilating shaft, this shelf serving as a place where baggage may be placed. 10 To enter the upper berth described the use of a ladder is necessary and a folding type is preferable inasmuch as a folding ladder could be stored in a compartment formed in the ends of the seats 6 and covered 15 by the hinged door 58.

Although a specific embodiment of the present invention has been illustrated and described, it will be understood that changes may be made within the scope of the appended claims without departing from the spirit of the invention, and such changes are contemplated.

What I claim is:

1. In a sleeping car having vertical side walls and a top lying directly upon said side walls and disposed in a single horizontal plane, a berth supported for vertical movement along one of said side walls and adapted to be moved into the corner formed by said wall and top, and means for maintaining said berth in raised and lowered positions respectively, and a ventilator shaft extending along said top and disposed beneath the upper edge of said side wall. 20 2. In a sleeping car, a double side wall, a vertical guide rod mounted in said wall, a movable berth within the car, guide members extending from said berth and mounted on said rod, and a spring surrounding said rod in engagement with said guide members and tending to balance the weight of said berth.

3. In a sleeping car, a double side wall, a vertical guide rod mounted in said wall, a 25 movable berth within the car, guide members extending from said berth and mounted on said rod, a spring surrounding said rod, one of said guide members resting on said spring, said spring being of insufficient strength to support said berth in raised position.

4. In a sleeping car, floor seats arranged in back to back relation, vertically slidable partitions mounted between the backs of adjacent seats, a berth supported for vertical 30 movement over said seats and between adjacent partitions, said adjacent partitions being adapted to guide said berth in vertical movement.

5. In a sleeping car, a double side wall, a 35 vertical guide rod mounted in said wall, a

movable berth within the car, and guide members extending from said berth and mounted on said rod, service appliances mounted in said double wall and accessible from the berth compartment.

6. In a sleeping car, a double side wall, a vertical guide rod mounted in said wall, a movable berth within the car, guide members extending from said berth and mounted on said rod, and hinged panels in the inner surface of said double wall, service appliances carried by said panels and adapted for concealment in said double wall, said appliances being accessible from the berth compartment on swinging said panels away from said wall. 70

7. In a sleeping car, a double side wall, a vertical guide rod mounted in said wall, a movable berth within the car, guide members extending from said berth and mounted on said rod, floor seats in said car, arranged back to back beneath said berth, vertically slidable partitions mounted between the backs of adjacent seats and adapted to guide said berth vertically, hinged panels in the inner surface of said double wall, and service appliances carried by said panels and adapted for concealment in said double wall, said appliances being accessible from the berth compartment on swinging said panels 75 away from said wall. 80

8. In a sleeping car, a berth supported for vertical movement, means for maintaining said berth in raised and lowered positions, respectively, an enclosing member in the upper portion of said car and adapted to contain said berth when in a raised position, a roller mounted in said enclosure, and a curtain mounted on said roller and having one end attached to said berth. 100

9. In a sleeping car, floor seats arranged in back to back relation, vertically slidable partitions mounted between the backs of adjacent seats, a berth supported for vertical movement over said seats and between adjacent partitions, said adjacent partitions being adapted to guide said berth in vertical movement, and means for sliding said partitions concealed in said seats. 110

10. In a sleeping car, a double side wall, a vertical guide rod mounted in said wall, a movable berth within the car, guide members extending from said berth and mounted on said rod, floor seats in said car, arranged back to back beneath said berth, vertically slidable partitions mounted between the backs of adjacent seats and adapted to guide said berth vertically, and means concealed in said seats for sliding said berth and partitions. 115

In testimony whereof I affix my signature.

WILLIAM YOUNG.
